DATA REPRODUCING MACHINE

James W. Bryce, Glen Ridge, N. J., assignor to
 International Business Machines Corporation,
 New York, N. Y., a corporation of New York

Application June 30, 1939, Serial No. 282,205

10 Claims.

(Cl. 95—4.5)

This invention relates to improvements in data reproducing machines and more particularly to improvements in film printing or reproducing machines wherein data are derived from a master colored film record and imprinted selectively upon one or more detail color film records.

The reproducing machine forming the subject matter of the instant application is intended for use with photographic control elements or records for statistical and accounting data, which control records upon reproduction are adapted for controlling the operations of the statistical machines in accordance with the data designations disposed thereon and also in accordance with the colors of the data designations imparted thereto. Controlling the statistical operations of suitable statistical and accounting machines forms no part of the present invention, therefore, no description of such operations will be given in the instant application.

The novel control elements which are used and reproduced in the present invention comprise a continuous strip of photographic color film, upon which are formed a plurality of individual records at successively spaced intervals along the film. The said individual records comprise groups of data designations in the form of discrete and differently colored control spots which are disposed in different positions in different columns on the records, so as to represent by their relative positions thereon the numerical control values thereof. The photographic control elements described in the present application are claimed in a separate and copending application Serial No. 208,086 filed May 14, 1938.

An object of the present invention resides in the provision of means for analyzing a master control record, of the type referred to, having colored data designations and upon sensing such data designations to control the reproduction or imprinting of the sensed data designations upon one or more detail control records.

Accordingly, provision is made whereby photographic control records are presented successively to a single analyzing or sensing station whereby the records are transilluminated so that the differently colored data designations are sensed and effective to control or condition suitably arranged light responsive means in accordance with the color of the sensed designations. The colored light rays set up by the control spots or data designations are directed to a plurality of photocells by means of light conducting rods, the said photocells being provided with different color filters so that one of them is effective to absorb or

block off the color rays from the associated photocell and thus condition it to render a suitable amplifying means operative for control purposes. Now, in the chosen illustration, means are provided whereby the operations of differentially positionable members are controlled in accordance with the values of the data control spots and also in accordance with the color of the sensed data control spots to reproduce upon one or more detail color films the colored control spots sensed, or if desired to reproduce the control spots in any predetermined and selected colors irrespective of the color of the sensed control spots. Provision is also made whereby the reproduction of the control spots in different and selected colors, irrespective of the color of the sensed spots, is under the control of a supplemental control spot appearing on the master film record.

Therefore, another object of the present invention resides in the provision of means under control of the colored data designations disposed on the master control elements for effecting reproduction of said colored data designations upon one or more detail control elements, or reproducing the designations upon the said detail elements in different colors than those formed on the master elements.

Another object resides in the provision of means, under control of a supplemental control spot on the master record, for effecting reproduction of the data designations upon one or more detail records selectively in different colors, irrespective of the colors of the sensed control spots representing the data designations on the master records.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a fragmentary section of a portion of the machine control element.

Fig. 2 is a diagrammatic view of the record analyzer.

Fig. 3 is a sectional view of the film feeding and analyzing means.

Fig. 4 is a plan view of the film feeding and analyzing means shown in Fig. 3.

Fig. 5 is a detail view of the film feeding means.

Fig. 6 is a sectional view of the film reproducing unit showing the essential elements thereof.

Fig. 7 is a plan view of the elements shown in Fig. 6.

Fig. 8 is a detail of the indicia slides.

Fig. 9 is a timing chart of certain of the control elements.

Figs. 10a and 10b when taken together form a wiring diagram of the control circuits of the machine.

Fig. 10c is a wiring diagram of a modified control circuit of the machine.

The control records will be described first followed thereby by a description of the novel record analyzer, then by a description of the different control units utilized in one form of reproducing machine adapted to be controlled by the control record and record analyzer.

Photographic control records

Referring now to Fig. 1, the photographic control element 20 shown therein is a fragmentary section of a continuous strip of photographic color film, provided with the usual feed apertures 24, upon which film are formed a plurality of individual records *a* to *e* comprising groups of data designations 22 in the form of discrete and differently colored control spots. One type of color film which is suitable for the purposes described in the instant application is the "Agfacolor" film which comprises a single unitary film structure consisting of a support upon which is coated in thin superimposed layers a plurality of light sensitive emulsions, each particularly sensitive to one of the primary colors. By exposing such a film to a colored object, three separate color records are recorded simultaneously, each sensitized layer recording the image to which it is color-sensitive. The color formation is brought about by the development of the film. Assume that the film 20 has been suitably exposed to record the data thereon in color and that the color formation of the data as designated is brought out by development of the recorded film.

The spot representation 21 on each record represents supplemental control data and the spot representations 22 represent amount data. The data represented by the reference character 23 are shown merely for interpreting the associated coded control spots and are not used for controlling machine operations. Assume that the data shown in the individual records *a* and *b* are formed in red color, the data in record *c* in blue, the data in record *d* in green, and the data in record *e* in black.

The spot representations 21 and 22 are photographic machine control spot representations and each set of numerical data comprises one or more control spots in such relative position, in different columnar areas, upon the film record as to represent by their relative position thereon the numerical control value thereof. In practice and according to the embodiment shown, such numerical spot representations are shown on the film in index point relation in general conformance with the manner in which index perforations are disposed on perforated record cards in the Hollerith accounting system. That is, the differential position of a control spot representation delineates the numerical value of a particular numeral. This will be clear by referring to the figure and particularly record *a* wherein the data represented by the designations or control spots 22 represent the amount twenty-seven. It is noted that the supplemental control spot 21 for each record is formed thereon in the "0" index point position of a selected column. The

purpose of this supplemental control spot will be understood as the description progresses.

It will be understood that the completed film has photographic reproductions thereon at successively spaced intervals along the film and that the reproductions are in extremely compact form, accordingly, a large quantity of statistical information can be placed on an extremely small controlling record.

Method of analyzing color of data designations

Referring now to Fig. 2 the method of analyzing the colored control spots formed on the film will now be explained briefly. Assume that the film 20 is advanced in the direction shown by the arrow past the sensing station which is represented by an aperture 25 in the opaque member 26, and that the color of the control spot presented to the said sensing station is red. Light rays emanating from a suitable source 27 are directed by the condenser 28 to the aperture 25 to permeate the section of the film presented to the said aperture. The red rays transmitted by the control spot are directed to different photocells 29a, 29b and 29c by means of the light conducting means comprising a three-way quartz rod member 30. Suitable light ray filters 31 to 33 are disposed between the individual legs of the quartz rod member and the associated photocells. Assume that the filter 31 is a cyan color filter designed to pass the different colored rays excepting red rays which are absorbed by this filter, that the filter 32 is a magenta color filter permitting the colored rays, with the exception of green, to pass therethrough and that the filter 33 is a yellow color filter permitting the colored rays, with the exception of blue, to pass therethrough.

Now, since the red light rays are directed by the individual legs of the quartz member 30 to the individual filters 31 to 33, it is understood that the said rays are permitted to pass through the magenta and yellow filters to impinge upon the associated photocells 29b and 29c, respectively, but are absorbed by the cyan filter so that no light rays are transmitted to the associated photocell 29a. Upon presentation of a blue control spot to the sensing station, it is seen that the cyan and magenta filters permit the rays to be transmitted to photocells 29a and 29b, respectively, whereas no blue light rays are transmitted by the yellow filter to the photocell 29c, and upon sensing a green control spot, light rays are transmitted to photocells 29a and 29c but not to photocell 29b. In the event that a black control spot is presented to the sensing station, no light rays are transmitted to any of the three photocells, namely, 29a to 29c.

Suitable amplifiers 34 are connected to the said photocells 29a to 29c (see Fig. 10a) in a manner well known in the art so that it is considered necessary only to state that when light rays are impinging on the photocells the associated amplifiers are conditioned so that no current flows in its output circuit, whereas, when no light rays are transmitted to the photocells the associated amplifiers are conditioned so that current flows in the output circuits thereof as long as the light rays impinge thereon. The purpose of this arrangement will be understood as the description progresses.

Film feeding and sensing means

Referring now to Figs. 3, 4 and 5, the photographic color film 20 is shown disposed on a supply spool or reel 35. The film is attached to

a take-up reel 36 and may be advanced by suitable driving connections cooperating with shafts 37 and 38 by means of suitable film feeding sprockets 39 and 40 secured to the said shafts, respectively, which sprockets cooperate with the film feed apertures 24 in the film. The film is fed past the analyzing station comprising the sensing aperture 25 and transilluminated by the light rays emanating from the light source 27 and directed thereto by the condenser 28. The said scanning aperture is arranged to present an opening sufficient to permit the scanning of a single transverse row of data or control spots only and is provided to extend transversely across the film record to any desired extent so as to permit the desired sections on the film to be sensed. The reference characters 29a, 41a and 42a designated in Fig. 4 represent the plurality of rows of photocells which are disposed at the analyzing station and controlled by the light rays impinging thereon. Each row of photocells, in the present illustration, comprises three photocells, for example, in Fig. 3, they are designated 29a to 29c. It is understood for each columnar area on the film, three individual photocells are provided and arranged as described. For each row or order of photocells a three way light conducting member 30 is provided, said member comprises a quartz rod member having three conducting legs for transmitting the light rays from the sensing aperture 25 to the associated photocells. The said quartz members are suitably supported by the block 43 and as mentioned the legs thereof extend from each photocell to the analyzing station where the common legs are positioned adjacent to one another along the sensing aperture. The spacing of the common legs of the quartz members along the said aperture is so arranged that each leg is positioned opposite one of the columns of control spots disposed on the film. In this manner the light rays directed to the sensing aperture can be conducted to the associated photocells to condition the latter for machine control operations during the sensing operations.

As mentioned before, individual color filters 31 to 33 are provided to be interposed between the individual legs of the quartz members 30 and the associated photocells. In Fig. 3, the color filters designated 31 to 33 are the cyan, magenta- and yellow color filters referred to hereinabove for the purposes set forth. It is understood that the three filters are provided for each order and interposed between the legs of the quartz members and associated photocells as shown in Fig. 3.

The film feeding means and control means therefor comprise generally the clutch magnet 44 and the associated pivoted armature 45 to which is secured a latch lever 46 normally engaging an extension 47 of the member 48 secured to shaft 38, and the clutch pawl 49 pivotally supported by member 48 and normally disengaged from the clutch element 50 by means of the said latch lever. Upon energization of magnet 44, the latch lever 46 is caused to release the pawl 49 to engage the clutch element 50 which is rotatably mounted on shaft 38 and rigidly secured to gear 51 which is driven by suitable means such as the drive pulley 53, secured to gear 52, and the associated driving connection 54. It is desired to feed the film with an intermittent motion therefore intermittent motion driving means is provided and comprises member 51a which is secured to gear 51 and member 52a which is secured to gear 52. Thus it is seen that whenever the driving connections

are operated and the magnet 44 energized that shaft 38 is rotated and in addition thereto gear 55, which is secured thereto, to rotate gears 56 and 57 the latter being secured to shaft 37, thereby rotating said shaft and causing the respective feed sprockets 40 and 39 to feed the film to the analyzing station. The control spots disposed on the film are then effective to modify the light rays emanating from the light source as described hereinabove for controlling the conditioning of the associated photocells.

The continuously rotating shaft 151 also drives the main drive shaft 78 of the reproducing unit by means of gear 76 which is secured to the latter shaft and gear 152 which is secured to shaft 151.

It should be mentioned that film supply control contacts 60 (Fig. 5) are provided and adapted to be closed by the suitably pivoted lever 61 as long as the film is presented to the analyzing station; however, when the film supply is exhausted the said lever swings to the left as viewed in Fig. 5 to open the contacts 60, the purpose of which will be understood as the description progresses. On shaft 37 a cam 63 is provided for controlling the contacts C1 (Fig. 10a) so that the said contacts are closed only at the times the index point positions are presented to the analyzing station as indicated in the timing chart in Fig. 9.

Film reproducing unit

30

Referring now to Figs. 6, 7 and 8 the film reproducing unit is shown to comprise a plurality of displaceable bars 155 which are suitably supported by the combs 156 and 157 so that the bars may be raised and lowered by means of the individual levers 158 which are connected to the related bars 155 by the interconnecting links 159. The bars 155 are provided with a plurality of ratchet teeth 160 which cooperate with stopping pawls 161 so that the upward movement of the bars may be interrupted at various positions to present the indicia slides 162 associated therewith opposite the different apertures 163 provided in the mask member 164. The pawls 161 normally are held in a latched position by latch members 165 so as not to engage the teeth provided in the said bars, but upon energization of the related magnet 166 the latch member releases the said associated pawl due to its partial rotation to the right as viewed in Fig. 6 by means of the connecting link 167 and cooperating extension member 168 of the magnet armature 169, thereby causing the associated pawl to interrupt the upward movement of the related bar.

The displacement of the said bars is controlled by the cam member 170 which is secured to the shaft 171, and upon rotation thereof the cam causes the cooperating yoke 172 and the shaft 173 to which the yoke is fastened to oscillate. The levers 158 are pivotally mounted on the shaft 173 and are urged against the crossbar 174 by springs 175, which crossbar is mounted in the oscillated yoke 172. Now, when the crossbar is raised, due to the rotation of cam 170, the individual levers 158 are urged in an upward direction and cause the connected bar 155 to be raised.

It is to be noted that the film 20 (which hereinafter will be referred to as the master film) is fed past its sensing station by the film feeding means described so that the differentially positioned spots thereon are sensed in a timed relationship with the upward movement of the bars 155, that is, for example, when a control spot is sensed in the "9" position, indicated on the mas-

ter film, an impulse is initiated at that time which is impressed upon the control magnet 166 to cause the related pawl 161 to be released and interrupt the upward movement of the said bar. The position of the interrupted bar is such that its associated indicator slide 162 is positioned opposite the aperture 163 in the mask 164 which is indicated "9". By virtue of the said spring connections, the bars 155 may be interrupted without interfering with the upward movement of the crossbar 174 which has an invariable extent of movement controlled by the cam 170.

The positioning of the indicator slides 162 opposite the different apertures in the mask determines the position of the control spot which is to be formed on the detail photographic film 176 when the camera section of the reproducer unit is operated. It should be mentioned that an individual bar 155, slide 162, and set of apertures 163 are provided for each column of data sensed on the master film. The mask 164 with the sets of apertures 163 is illuminated by the light sources 173 and is suitably disposed within the focal range of the lens system 177 so that upon operation thereof by means of link 178, a photographic record of the indicia set up appearing on the mask 164 is made. Disregarding for the moment the color values of the spots, it is evident that the record formed on the detail film 176 will be a reproduced record of the sensed record of the master film. Assume that the record "a" of the master film 20 (see Fig. 1) is fed past the sensing stations and that the differentially timed impulses initiated upon sensing of the control spots 22 are impressed upon the individual magnets 166 to interrupt the movement of the bars so that the positioned indicator slides 162 are opposite certain of the apertures 163 to form a pattern of control spots on the mask 164 to conform to the pattern of control spots sensed on the said record of the master film. Now, upon operation of the lens system 177 the said pattern formed on the mask is recorded upon the detail film 176 which record upon development and printing thereof will have the differentially positioned control spots formed thereon in the same positions as those of the control spots on the said record of the master film. In this manner any desired number of records may be reproduced upon detail films.

Provision is made whereby the lens system is not operated until all the indicator slides 162 have been positioned in conformance with the sensed control spots. This means comprises the link 178, lever 180 and cam 181, the latter being secured to gear 182, and secured to gear 182 is a mutilated gear 183 carrying a Geneva drive disk 184. The said cam 181 and gears 182 and 183 are rotatably mounted on a stud 185. Gear 182 is in mesh with the gear 186 which is loosely mounted on the continuously rotating shaft 78. Secured to shaft 78 is a clutch disk 187 which drives the associated pawl 188 upon release of the pawl. This pawl is pivotally mounted on a member 189 which in turn is fastened to gear 186. The pawl 188 and member 189 normally are latched by the latch member 190 which is shown as an integral part of the armature 191 of magnet 192. Upon energization of the said magnet the pawl is released to engage the clutch disk 187 and be driven thereby to rotate the associated gear 186 and in turn rotate gears 182 and 183, cam 181 and disk 184. Rotation of cam 181 causes the shutter of the lens system 177 to be cocked by means of the cam follower lever 180 and link 178 and when

the lever 180 drops off the high point of the cam causes the shutter of the lens to be operated, exposing the detail film to the indicia set-up on the mask. The cam 181 is positioned so that this operation occurs near the end of the machine cycle. Upon exposure of the detail film it is advanced sufficiently so that the next frame is in position for recording the following indicia set-up formed by the indicia slides. The film advancement is effected by the gear 183 and disk 184 which, during most of the machine cycle, engages the complementary disk 193, the latter disk being secured to gear 194. Upon disengagement of the Geneva disks the effective sector of the gear 183 engages gear 194 and rotates the latter sufficiently thereby rotating the film feed sprocket 195 which is secured to gear 194 and advancing the detail film 176 to present an unrecorded section thereof to the lens system.

The detail film 176 which in the instant application is a color film similar to the master film described is fed from the supply reel 196 by the feed sprocket 195 to the lens system 177 and thence to a take up reel 197. Suitably disposed contacts 198 are provided and held in a closed position by lever 199 as long as the film supply remains unexhausted for purposes to be set forth hereinafter.

It should be mentioned that gear 186 when rotated by shaft 78 also drives the gear 200 which is fixed to shaft 171 to rotate the cam 170 for controlling the positioning of the said bars 155. From the description up to this point it is seen that the feeding means for the master film, the feeding means of the detail film, the operating means of the lens system 177, and the operating means of the indicia slides 162 are all operated in a predetermined timed relationship due to the described interconnecting gearing arrangement.

The mechanism for setting up the color code 40 of the indicia slides 162 will now be described. Each of the differentially settable indicia slides 162 comprises a tubular member which is divided into differently colored sections. In Fig. 8 four differently colored sections are indicated by the reference characters 162a to 162d and the colors selected for the said sections in the present illustration are black, red, blue, and green respectively. The indicia slides not only are slidably arranged on the supporting shafts 201 but are also keyed thereon and capable of being rotated by the said supporting shafts.

On the shaft 171 a gear 202 is secured, which gear is in mesh with gear 203, the latter being rotatably mounted on the stud 204. Secured to gear 203 is a cam 205 provided with a suitable cam groove for oscillating the associated follower yoke 206 about the shaft 207. A yoke 208 similar to yoke 206 is oscillated by the latter by means of the interconnecting links 209. Individual arms 210 are provided and at one end are secured to individual tubular shafts 211, which shafts are connected to individual levers 212. Now, it is seen that arms 210 are adapted to follow the movements of the yoke 208 since the said arms are constantly urged against the yoke 208 by means of the individual springs 213, each of which are secured at one end to yoke 206 and at the other end to arm 210. In this manner the related tubular shafts 211 are rotated to displace the associated levers 212 which in turn are effective to displace the racks 214 by means of the connecting links 215. The settable racks 214 are adapted to rotate the settable gears 216 which in turn are in constant engagement with

the elongated gear 217. The degree of rotation imparted to gear 217 is dependent upon the movement of the related arm 210. The means for controlling the movement of the arms 210 will presently be described. Upon rotation of gear 217, which is secured to shaft 201, the indicia slides are rotated irrespective of their vertical position on the shaft 201 to present to the apertures in the mask 164 the desired colored 10 sections of the tubular member which comprises the indicia slide. It is understood that individual gears 216 and 217, shafts 201 and slides 162 are provided for each column of data sensed on the master film and desired to be reproduced on the 15 detail films. It is evident that the degree of rotation of the indicia slide determines the color of the data set up or formed on the mask. This degree of rotation is determined by the movement of arm 210, and the extent of the movement of the said arm is controlled by the 20 associated magnet 218. During the movement of the arms 210 in a clockwise direction the related magnets 218 are energized by impulses initiated at differential times in the cycle, which timed 25 impulses are representative of the different colors.

When a magnet 218 is energized the pivoted stop pawl 219 is caused to engage one of the notches 220 formed in the arm 210 thereby interrupting further movement of the said arm, 30 and in this manner determining the degree of rotation to be imparted to the related indicia slide 162. In this manner a color code is set up or formed on the mask in accordance with the initiated differentially timed impulses which 35 are representative of and determine the color code to be recorded on the detail films by the reproducing unit.

It is to be noted that the gears 216 are mounted on elongated sleeves 221 supported by the 40 shafts 222. At one end of each sleeve provision is made whereby a related pivoted selecting lever 223 can cooperate with the sleeve to position the related sleeve and gear 216 in four different positions in accordance with the position of lever 223. In this manner the movement of any desired rack 214 can be transmitted to the indicia slide in accordance with the setting of the associated gear 216. It should also be mentioned that suitable cams similar to the one designated 45 224 are secured to the shaft 171 to control the operations of the associated CC contacts (see Fig. 9).

Operation of the machine

55 Referring now to Figs. 9, 10a and 10b the description of the operation of the machine will be given. Assume that it is desired to reproduce on a detail colored film the colored control spots as they appear on the master film and in the same color code. Assume that the colored photographic films are properly arranged in the sensing and reproducing units, that the light sources 21 and 179 are energized, and that the switches S1 are closed when the start key 60 SK1 is depressed to close the associated contacts 225. A circuit is then established from conductor 226 through contacts 227 of the stop key SK2, contacts 225, relay R1, and magnets 44 and 192 to conductor 228, energizing said relay and magnets 65 nets. Closure of contacts R1a sets up a holding circuit for the said relay and magnets through the normally closed contacts 227 and the contacts 60 and 198 which are closed at this time, thus conditioning the machine for continuous 70 operations. Energization of the magnet 44 is

effective to start the master film feeding means into operation thereby advancing the individual photographic records past the sensing aperture 25 so that sensing and analyzing of the differentially positioned and colored control spots representing the data can be effected as described hereinabove. Energization of the magnet 192 starts the operations of the film reproducing unit which is effected in timed relationship with the sensing operations. The different index point 10 positions on each record of the master film are presented to the sensing station in synchronism with the displacement of the indicia slides 162. When the "5" index point position is sensed on a record of the master film, the indicia slide 162 is displaced at this timed interval to be opposite the "5" aperture of the mask 164. 15

Now assume that the first records sensed on the master film 20 have the differentially positioned control spots formed thereon in red color. Upon sensing the differentially positioned red control spots the light rays are prevented from impinging on the photocells opposite the cyan color filters in each of the columns in which the red control spots are sensed. In the present illustration, it is then understood, that the photocells 29a, 41a, and 42a are not exposed to the light rays upon sensing the red control spots. It is understood that under these conditions the 20 amplifiers 34 associated therewith are rendered conductive to energize the relays AR, 25 BR and CR. 30

Due to the closure of contacts AR1, BR1, and CR1 differentially timed impulses are initiated 35 at the times the said relays are energized and impressed upon the related magnets 166 which control the positioning of the associated bars 155 and indicia slides 162. One of these circuits can be traced as follows: conductor 226, contacts C1, contacts AR1, conductor 229, magnet 166 to conductor 228, energizing said magnet and causing the related stop pawl 161 to engage the associated bar 155 and interrupt further displacement thereof, thus effecting the positioning of the associated indicator slide 162 opposite the aperture 163 corresponding to the data represented by the sensed control spot on the master film. 40 45

Upon closure of contacts AR3, a circuit is established from conductor 226 to contacts C1, AR3, AB3 and coil of relay R3 to conductor 228, 50 energizing said relay and establishing a holding circuit therefor through cam controlled contacts CC1 (closed during all of sensing portion of cycle) and contacts R2a. The said relay is kept energized until near the end of the machine cycle, 55 that is until contacts CC1 are opened (see Fig. 9). Relays R7 and R11 are energized and maintained energized exactly in the same manner as described for relay R3.

It is noted that relays R2, R6 and R10 represent the color black for the respective columns, relays R3, R7 and R11 represent red, relays R4, R8, and R12 represent blue, and relays R5, R9, R13 represent green, that is, upon sensing these colored spots in the individual columns of the 60 master film the said relays associated with those columns are energized accordingly. Now, closure of the contacts R3b, R7b and R11b partially complete or condition for energization the circuits extending to the control magnets 218. The magnets 218 are energized at differential times in accordance with the closure of the cam controlled contacts CC2, CC3, CC4 and CC5. Whenever these contacts are connected in a conditioned 65 circuit as described, the said contacts, upon 70

closure, initiate differentially timed impulses which are indicative of certain colors, for example, the timed impulses initiated by contacts CC2 represent black, those impulses initiated by contacts CC3 represent red, impulses initiated by contacts CC4 represent blue, and those initiated by contacts CC5 represent green.

The configuration of cam 205 (Figs. 6 and 7) is such that the arms 210 are displaced during 10 the portion of the machine cycle when contacts CC2 to CC5 are closed and in synchronism with the operation of these contacts, that is, for example when contacts CC3 are closed, the arms 210 are positioned so that the indicia slides are 15 rotated sufficiently to present the red colored section of the tubular member opposite the apertures of the mask.

It is now understood that upon closure of the 20 CC3 contacts the partially completed circuits just referred to are now completed as the positioned 25 indicia slides are conditioned to present the red sections thereof to the apertures in the mask. Magnets 218 are then energized to render the stop pawls 219 effective to hold the arms 210 in the 30 position so that the indicia slides represent the color red until a recording of the data pattern 35 formed on the mask is made. The circuits for effecting energization of the magnets 218 are as follows: conductor 226, contacts CC3, conductors 230, contacts R3b, R7b and R11b, conductors 231 and magnets 218 to conductor 228.

Now it is seen that the indicia slides are differentially positioned in accordance with the data sensed on the master film and the said slide are 35 also conditioned so as to conform in color to the colored control spots sensed on the master film. The colored pattern formed on the mask 164 corresponds to the pattern of colored control spots sensed on the master film. A recording of this 40 pattern is now made and occurs shortly before the end of the machine cycle when the cam 181 (Fig. 6) is effective to operate the lens system 177, thus, recording the colored pattern upon the unrecorded frame of the color detail film 176. 45 As described hereinabove immediately after recording of the data set-up is effected, the film 176 is advanced by means of the Geneva drive (gear 183, disks 184 and 193) to present an unrecorded section of the color film to the lens system. Contacts CC1 are then opened near the 50 end of the machine cycle to effect deenergization of those energized relays of the group R2 to R13 thus permitting the arms 210 and indicia slides 162 to be restored to the normal position. The 55 restoring of the displaced parts to normal position is effected during the last four points of the machine cycle as indicated on the timing chart. The configuration of the bars 155 are such that the top portions thereof are adapted to 60 restore the latch levers 165 and pawls 161 to normal positions.

In the description just set forth reproduction of the exact color pattern was considered only, however from the description set forth it is understood now that the color pattern reproduced on the detail film need not correspond to the color pattern or code of the master if so desired. One method of selectively altering the color pattern recorded on the detail film is by selectively setting the levers 223 so that the associated gears 70 216 engage different racks 214, thus it is seen that the color of the spot recorded in each column of the detail film can be selectively controlled. Another method of selectively controlling the 75 color pattern recorded is by transposing

the plug connections from the cam controlled contacts CC2—CC5 to the contacts R2b—R13b.

Still another method of selectively controlling the color pattern recorded on the detail film is by controlling the color selections automatically 5 under control of a supplemental colored control spot which is shown and indicated by the reference character 21 in Fig. 1. Assume, for example, that this supplemental spot is in the "0" index point position whenever it appears on 10 the individual records and for the moment assume that its color is the same as the color of the amount data control spots 22.

Referring now to Fig. 10c and assuming that the machine is conditioned for continuous operation as described hereinabove, and that the color of the control spots (supplemental and amount data control spots) in each frame or record of the master film are all similar, that the color of the spots on the records, which are sensed at this 15 time, are formed in red color, and that it is desired to reproduce only the amount data on the detail film.

Upon sensing the red control spots at the differential times the AR, BR and CR relays are energized similarly as described hereinbefore.

Closure of the contacts BR1 and CR1 effect energization of the control magnets 166 to position the indicia slides 162 to correspond to the differential positioning of the control spots representing the amount data on the master film.

Closure of the contacts AR3 at the "0" index point position causes relay R3 to be energized and maintained energized through its contacts R3a similarly as described hereinabove. A circuit is 35 also established from conductor 226 to contacts C1, AR3, AB3, conductor 235, contacts CC7, coil of relay R14 and conductor 228 energizing said relay to establish a holding circuit therefor. The said holding circuit which extends through contacts R14a and CC6 is maintained until near the end of the machine cycle (see Fig. 9). Energization of relay R14 causes the "C" contacts to be 40 closed and "b" contacts to be opened. Now it is seen when the CC2—CC5 contacts are closed sequentially that a circuit is established from conductor 226, contacts CC4, conductor 236, contact "c", conductor 231, contacts R3b to magnet 218 and conductor 228. The timed impulse impressed upon the said magnet represents blue, that is 45 magnet 218 is energized to interrupt the related arm 210 so that its rack 214 is displaced sufficiently to position all those indicator slides which are connected to the rack by the gears 216. The color pattern now set up or formed on the mask 50 is one in blue instead of red as on the record of the master film.

When no supplemental control spots are sensed on the records on the master film, or if the said supplemental spots are formed in colors other than red, relay R14 is not energized, therefore the "b" contacts of relay R14 remain closed and the original color record on the master film is reproduced on the detail film just as described hereinabove. Of course it is obvious that the red 65 supplemental control spot can be formed on other records wherein the data control spots are formed in black, blue, or green colors. The wiring diagram in 10c is arranged that the red amount data spots are changed to blue whenever a red supplemental control spot is sensed, blue amount data spots to red, black amount data spots to green, and green amount data spots to black. It is not intended to be limited to the specific example shown concerning the reproduction of the colored 70 75

spots on detail films in colors other than those in which the amount data are formed on the master film. From this description it is seen that many plugging arrangements for the interconnecting conductors can be made so that many additional color code combinations can be formed. For example by duplicating the control elements described in Fig. 10c the colors of predetermined columns on the records can be selectively altered with respect to each other. In fact each control spot in the different columns can be of varying colors rather than all be formed in the same color as assumed in these illustrations. Automatic controlling from the colors of the spots in any column can then be effected exactly as just described to alter its color when recorded on the detail film. It is also obvious that more than one detail film can be produced at one time, by providing a plurality of the reproducing units described and connecting the control magnets in multiple in the circuits described, a plurality of detail films can be reproduced at one and the same time.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A data reproducing machine of the character described controlled by individual records having data designations disposed thereon which are formed in different colors on the different records comprising means for sensing the colored data designations, said designations on each record being disposed at different positions on the record to denote the different values of the data, means included in the sensing means for analyzing the colors of the different designations, and recording means for reproducing in color the data designations, said recording means comprising differentially settable members, each member having a plurality of different colored sections formed thereon, means under control of the sensing means for controlling the differential settings of the said members, additional means under control of the sensing means for controlling the settings of the said differently colored sections of the members to conform to the color of the sensed and analyzed data designations, and means for recording photographically in color the colored pattern formed by the settable members.

2. The invention set forth in claim 1 in which means are provided for rendering the said additional means effective for controlling the setting of the said differently colored sections of the members only after the said differential setting of the members has been effected.

3. A data reproducing machine of the character described comprising means for feeding individual records having data designations disposed thereon which are formed in different colors on the different records, said data designations on each record comprising colored control spots which are disposed at different positions on the record to denote the different values of the data, means for sensing at differential times the differentially positioned colored control spots including means for analyzing the colors of the sensed control spots, and recording means for

reproducing in color the data designations, said recording means comprising settable indicating members, each member having a plurality of different colored sections formed thereon, means for displacing the members in a timed relationship with the sensing of the differentially disposed control spots on the records, means under control of the sensing means for interrupting further displacement of the said members upon sensing of the related control spots, additional means under control of the sensing means for controlling the setting of the said differently colored sections of the members to conform to the color of the sensed and analyzed control spots, and means for recording photographically in color the colored pattern formed by the said interrupted members.

4. A data reproducing machine of the character described comprising means for feeding individual records bearing data designations which are formed in different colors on the different records, said designations on each record comprising colored control spots which are disposed at different positions on the record to denote the different values of the data, means for sensing the differently positioned and colored control spots comprising a source of light rays and light responsive means conditioned by the light rays modified by the said control spots, additional means included in the sensing means for analyzing the colors of the sensed control spots for controlling the conditioning of the light responsive means, and recording means for reproducing in color the data designations, said recording means comprising an opaque mask having individual apertures disposed along a vertical line, settable indicating members disposed on one side of the mask, each member having a plurality of different colored sections formed thereon, means under control of the conditioned light responsive means for controlling the differential setting of the said members with respect to said apertures, additional means under control of the said conditioned light responsive means for controlling the setting of the said differently colored sections of the members to present certain of the colored sections of the apertures, and means disposed on the other side of the mask for recording photographically in color the colored pattern formed on the mask by the settable members.

5. A data reproducing machine of the character described controlled by individual records bearing data designations which are formed in different colors on the different records, said designations on each record being disposed at different positions thereon to denote the different values of the data, means for sensing the colored data designations disposed on the individual records, means under control of the sensing means for initiating differentially timed impulses to represent the data formed at the different positions on the records, means included in the sensing means for analyzing the colors of the different designations, and means under control of the last mentioned means for initiating additional timed impulses for representing the different colors sensed, and recording means for reproducing in color the data designations, said recording means comprising differentially settable members, each member having a plurality of different colored sections formed thereon, means controlled by the said differentially timed impulses for controlling the differential setting of the said members, additional means controlled

by the said additional timed impulses for controlling the setting of the said differently colored sections of the members, and means for recording photographically, in color the colored pattern formed by the settable members.

- 5 6. In a data reproducing machine of the character described controlled by a photographic control element having a plurality of individual records bearing data designations, said designations comprising colored control spots which are differentially positioned in various columns to represent by their relative positions therein the different values of the data, means for sensing the said control spots comprising individual light source means and light responsive means for each column to be sensed, means included in the sensing means for conditioning the related light responsive means in accordance with the color of the sensed control spots upon sensing of the 10 control spots, and recording means for reproducing in color the sensed data designations, said recording means comprising individual settable members, one for each column sensed, each member having a plurality of different colored sections 15 formed thereon, means under control of the conditioned light responsive means for controlling the differential settings of the said members in accordance with the data values sensed in the corresponding columns, additional means under 20 control of the conditioned light responsive means for controlling the settings of the said differently colored sections of the members, and means for recording photographically in color the colored pattern formed by the settable members.
- 25 7. In a data reproducing machine of the character described controlled by a photographic control element having a plurality of individual records bearing data designations, said designations comprising colored control spots which are differentially positioned in various columns to represent by their relative positions therein the different values of the data, means for sensing the said control spots at differential times comprising individual light source means and a plurality of light responsive means for each column 30 to be sensed, means included in the sensing means for conditioning selectively certain of the light responsive means in accordance with the colors of the sensed control spots, means under control 35 of the sensing means for initiating differentially 40
- 45 50

timed impulses at such times when the said light responsive means are conditioned upon sensing the said spots, additional means under control of the sensing means for initiating additional timed impulses representing the analyzed colors of the sensed control spots, and recording means for reproducing in color the sensed data designations, said recording means comprising individual settable members, one for each column sensed, each member having a plurality of different colored sections formed thereon, means controlled by the said differentially timed impulses for controlling the settings of the said settable members, means controlled by the said additional timed impulses for controlling the settings of the differently colored sections of the said members, and means for recording photographically in color the colored pattern formed by the settable members.

10 15 8. The invention set forth in claim 7 having further means controlled by the said additional timed impulses for controlling the settings of the said colored sections of the members to indicate the data designations in colors different from the colors of the sensed control spots.

20 25 9. In a data reproducing machine of the character described controlled by individual records having data designations disposed thereon which are formed in different colors on the different records, said designations on each record being disposed at different positions thereon to denote 30 the different values of the data, certain of the said records being provided with supplemental colored designations, means for sensing the colored data and supplemental designations including means for determining the colors of the 35 sensed designations, data reproducing means under the control of the sensing means comprising means for reproducing on individual records in color the sensed data designations, and means under control of the sensed supplemental designation for determining the colors in which the reproduced data designations are to be formed irrespective of the colors of the sensed data designations.

40 45 10. The invention set forth in claim 9 having further means for rendering the said last mentioned means effective only when the sensed supplemental designations are formed in selected predetermined colors.

JAMES W. BRYCE. 50
